James F. Williamson

UNITED STATES PATENT OFFICE.

EDWIN C. WASHBURN, OF ENGLEWOOD, NEW JERSEY.

SIDE-FRAME AND BOLSTER SPRING BEARING.

1,411,763.

Specification of Letters Patent.

Patented Apr. 4, 1922.

Application filed November 24, 1920. Serial No. 426,290.

To all whom it may concern:

Be it known that I, EDWIN C. WASHBURN, a citizen of the United States, residing at Englewood, in the county of Bergen and State of New Jersey, have invented certain new and useful Improvements in Side-Frame and Bolster Spring Bearings, and I do hereby declare the following to be a full, clear, and exact description of the invention, such as will enable others skilled in the art to which it appertains to make and use the same.

This invention relates to a bearing structure for the bolster and the truck side frame of a railway car and is particularly shown as a bearing for the supporting springs upon which the ends of the bolster rest.

It is an object of this invention to provide such a spring bearing which will permit of lateral swaying movements of the bolster without detachment of the same from the springs and without lessening of the spring support.

This and other objects of the invention will be apparent from the following description in connection with the accompanying drawings, in which—

Fig. 1 is a view in side elevation of a railway side frame and the bolster and bolster springs carried thereby;

Fig. 2 is a central section through the bolster and side frame taken on the line 2—2 of Fig. 1; and

Fig. 3 is a sectional plan taken approximately on the line 3—3 of Fig. 2.

Referring to the drawings, the side frame *a* of usual construction is shown as comprising compression and tension members and also a tie member, which members are connected by the vertically disposed bolster columns which form the receiving means for the ends of the bolster. The bolster *b* which extends between the side frames at opposite sides of the car, is also shown as having compression and tension members joined at the center by the usual central member. The side frame and bolster shown and above referred to are of a known construction and such members have been illustrated and described in detail in my prior pending applications, Ser. No. 389,995, filed June 18th, 1920 and Ser. No. 389,997, filed June 18, 1920. Tie members or planks *c* extending between the side frames on opposite sides of the car, are also shown in Fig. 2.

The spring bearing structure to which the

present invention is directed, is duplicated on opposite sides of the car and the description of the same on one side of the car will be sufficient to understand the structure 60 thereof.

The side frame is provided with a spring buffer or bearing plate 1 extending between the bolster columns near the lower end thereof and this plate is surrounded at its upper 65 edge by a light flange 2. The surface of the plate is arranged to receive a series of nested coiled springs and the said surface is formed to incline toward the center of the car at a slight angle. While this angle may vary 70 within certain limits, an angle of substantially five degrees has been found suitable and efficient in actual service. As shown, four series of springs 3 are disposed upon the bearing plate 1 and these springs receive the 75 weight of and support the bolster *b*. A convenient number of thin plates or shim members 4 are in direct contact with the springs and these shim members rest upon the plate 1 and also against a spring buffer or bearing 80 plate 5 carried by the bolster. This plate 5 also has a surrounding flange depending from the bearing surface thereof which is of somewhat greater height than the flange 2. The bearing surface of the plate 5 is also 85 arranged at slight angles to a horizontal and inclined toward the center of the car, so as to be in substantial parallelism with the surface of the plate 1.

The ends of the plank *c* are secured to 90 plates 1 by being disposed in sockets in said plates and having metal *c*¹ cast into said sockets around said ends, the members 1 and 2 therein forming a spring plank of strong and rigid construction.

As shown in Fig. 1, the plate 5 is equipped with lateral portions movable in slots *a*¹ of the side frame. When the bolster moves inwardly and the springs 3 are sufficiently flexed, said portion will rest on the 100 bottom of slot *a*¹ and be supported on the side frame.

In assembling the parts of the side frame the spring plates 1 and member *c* forming the spring plank can be inserted between the 105 sides of the bolster columns of said frame *a* and then slid downwardly to its seat.

The bolster is thus supported at its end upon springs carried between the two inclined bearing surfaces. When the car receives a 110 lateral impulse or sways from side to side, the bolster can move, for instance, to the

left, as seen in Fig. 2, and the springs will be carried to a vertical or slightly past a vertical position. This will result in a slight rising movement of this end of the bolster and the springs will be under torsional strain. The swaying movement toward the left is thus resisted by the springs on the left side, and the swaying of the weight of the bolster toward right will, in like manner, be resisted by the swaying movement in that direction. Owing to the inclined position of the spring bearing plates, there will be practically no tendency for the springs to be dislocated and such tendency, if any, will be resisted by the flanges which extend slightly beyond the bearing ends of the springs.

It will also be within this invention to have the seat for the two contact springs, at one end of the structure, and the seat for the inside pair of springs at the same end inclined toward each other, thus forming a pair of seats inclined toward each other at each end of the structure. With such an arrangement the load will be distributed more evenly and the returning power of the springs will be exerted from both ends of the bolster.

It is thus seen that applicant has produced a spring bearing for a bolster which will permit of a swaying or lateral movement of the bolster without dislocation of the springs and which will be resisted yieldingly by the springs. The springs will at the same time continue to support the load and there will be no lessening of the spring effect in this direction. The shims 4 will be used in sufficient number to insure that the springs will be under proper tension for the known weight of the car.

It will, of course, be understood that various changes can be made in the form and details of the device without departing from the scope of applicant's invention, which, generally stated, consists in the matter shown and described and set forth in the appended claims.

What is claimed is:

1. A bearing for the bolster and side frame of a railway car having in combination bearing surfaces at the ends of said bolster, oppositely disposed bearing surfaces on said side frames, the bearing surfaces on the bolster and side frame being in substantial parallelism and inclining slightly toward the center of the car, and springs disposed between said bearing surfaces.

2. A spring bearing for a bolster and side frame structure having in combination a bearing plate on said side frame, a plurality of springs supported thereby, and a bearing plate on said bolster adapted to rest upon said springs, said latter plate being inclined at a slight angle toward the center of the car.

3. A spring bearing for bolster and side frame structure having in combination a bearing plate on said side frame inclined at a slight angle toward the center of the car, coiled springs carried by said plate and inclining at a corresponding angle inwardly toward the center of the car and a bearing plate carried by the bolster and bearing upon said springs.

4. A spring bearing for a bolster and side frame structure having in combination a bearing plate on said side frame secured to and between the bolster columns thereof, said bearing surface inclining at a slight angle to the horizontal toward the center of the car, coiled springs carried by said bearing surface and hence, inclining at a slight angle to the vertical toward the center of the car, and a bearing surface carried by the bolster and resting upon said springs, said latter bearing surface also inclining at a similar angle toward the center of the car.

5. A spring bearing for bolster and side frame structure having in combination a bearing plate on the side frame having a surface inclined at a slight angle toward the center of the car, a bearing plate on the bolster having a surface in substantial parallelism with said surface, springs carried by the first mentioned plate upon which the second mentioned plate rests, and flanges on said plates surrounding the same and enclosing the ends of the springs.

6. A truck structure having set inclined springs interposed between its bolster and spring carrying portion, said bolster being mounted for endwise movement whereby said springs will be flexed by said endwise movement.

7. A truck structure including a bolster arranged for endwise movement and having oppositely inclined springs interposed between said bolster and the spring carrying portion.

8. A truck structure comprising nested springs inclined toward one another in a direction transversely of the truck.

9. A truck structure having side frames, bolster springs and a spring plank, said plank consisting of spring bases and a connecting section, said bases being cast to the connecting section.

10. A truck structure comprising a side frame and a bolster, said parts each consisting of cored spring plates and connecting portions, said plates being arranged to receive the connecting portions and to be secured thereto by cast fillers.

In testimony whereof I affix my signature in presence of two witnesses.

EDWIN C. WASHBURN.
